LIEVI DAVIS.
BY E. M. HARRINGTON.

UNITED STATES PATENT OFFICE.

LEVI DAVIS, OF ALTON, ILLINOIS.

LOCKING DEVICE FOR INCANDESCENT-ELECTRIC-LAMP BULBS.

933,296.

Specification of Letters Patent. Patented Sept. 7, 1909.

Application filed March 15, 1909. Serial No. 483,577.

To all whom it may concern:

Be it known that I, LEVI DAVIS, a citizen of the United States of America, residing in Alton, county of Madison, and State of Illinois, have invented certain new and useful Improvements in Locking Devices for Incandescent-Electric-Lamp Bulbs, of which the following is a full, clear, and exact description, reference being had to the accompanying drawings, forming part of this specification.

My invention relates to a locking device for use in the sockets of incandescent electric lamps whereby theft of the lamp bulbs may be prevented.

Figure I is an elevation of an incandescent electric lamp having my locking device applied thereto. Fig. II is an enlarged view, partly in elevation and partly in longitudinal section, illustrating my improvement. Fig. III is a cross section taken on line III—III, Fig. II. Fig. IV is an elevation of the neck of a lamp bulb having a stop thereon adapted to receive my locking device. Fig. V is a similar view to Fig. IV illustrating another manner of producing the stop for the locking device. Fig. VI is an enlarged elevation of the locking screw of my device. Fig. VII is an end view of the locking screw. Fig. VIII is an elevation of the key by which the locking screw may be operated. Fig. IX is an end view of the key shown in Fig. VIII. Fig. X is in part a longitudinal section through a modification of the ring of my locking device and a lamp bulb, and in part an elevation of the neck of a lamp bulb seated in the socket.

In the accompanying drawings: A designates the socket of an incandescent electric lamp, this socket being provided at its end with one or more slots or openings B, (see Fig. II).

C is a lamp bulb having upon its neck the screw-threaded shell D adapted to be entered into the socket A in the usual manner.

Referring now to my locking device, I designates a locking ring that is adapted to be fitted to the lamp socket A and which is provided with a screw threaded aperture 2, and has at its lower end an annular flange 3 that extends inwardly from the main body of the ring.

4 is a locking screw having a screw threaded body 5 that enters into the aperture 2 in the locking ring, and a stem 6 that is adapted to protrude past the inner face of the lock-

ing face of the locking ring and into the socket A. The shank 7 of the locking screw is adapted to receive a key 9, shown in Figs. VIII and IX, and in order that the locking screw may be operated by the key, the shank is provided with a flattened side 8 which is adapted to receive the flat face 10 within the socket of the locking key, (see Fig. IX,) the remainder of the said key socket being segmental in shape.

The locking screw 4 of my device is adapted to be introduced into the locking ring of the device to such a degree as to cause the stem of said screw to be moved inwardly to an extent sufficient to position the end of the stem close to one of the threads upon the shell of the lamp bulb C. When the screw is entered into the locking ring to the extent just stated, its stem occupies a position in the path of travel of the stop d projecting from the thread of the lamp bulb shell, (Fig. IV.) Or, in lieu of said projecting stop, I may produce in the thread of the shell a recess d', (see Fig. V,) into which the stem of the locking screw may enter. The locking screw in its extension from the locking ring also passes through the opening B in the lamp socket, and as a consequence, the lamp socket serves to prevent rotation of said locking ring so that when the locking screw is in impingement with the stop portion of the lamp bulb, the locking ring is held from rotation upon the socket and removal of the lamp bulb from the socket is prevented due to the engagement of the locking screw with the stop portion of the lamp bulb shell.

To prevent the locking ring being slipped down on the socket, and onto the neck of the lamp bulb with the result of withdrawing the locking screw from the slot or opening in the lamp socket, I provide the locking ring with an inwardly extending flange 3 which bears against the tapering neck of the lamp bulb, (as seen in Fig. II,) and by so doing permits of the lamp bulb holding the locking ring in its proper position.

The body 5 of the locking screw 4 is made larger than the shank 7 of said screw, and the aperture 2 in the locking ring corresponds in diameter to said body. This construction provides for the shank of the locking screw entering into the aperture in the locking ring, (as seen in Figs. II and III,) with a sufficient space around it to permit the introduction of the screw engaging end

of the key 9 into said aperture when the screw is wholly introduced into locking engagement with the shell of the lamp bulb. The shank of the screw is therefore unexposed when the lamp bulb is locked in the socket, and due to the peculiar shape of the shank of the locking screw, it is extremely difficult to operate the locking screw without the use of the key 9 provided especially for the operation of said screw, and which is not intended to fall into the hands of any one who might attempt theft of the lamp bulbs.

In Fig. X, I have shown a modification in which the locking ring 1^a is, instead of being provided with an inwardly extending flange 3, (as shown in Fig. II,) made of the proper width to permit of its being engaged by the lamp bulb when said bulb has been entered into the lamp socket, thereby causing the bulb to hold the locking ring from downward movement upon the socket to a degree sufficient to permit the escape of the locking screw 4 from the opening B in the socket.

I claim:

1. The combination with an incandescent electric lamp socket and a bulb seated therein, of a ring fitted to said socket, and a locking member movable in said ring through said socket into engagement with said bulb.

2. The combination with an incandescent electric lamp socket and a bulb seated therein, of a ring fitted to said socket, and a locking screw in said ring extending through

said socket and into engagement with said bulb.

3. The combination with an incandescent electric lamp socket, of a ring fitted to said socket, and provided with a screw-threaded aperture, and a screw in said screw-threaded aperture extending through said socket into engagement with a lamp bulb shell seated in the socket; said locking screw being provided at its outer end with a key receiving shank of less diameter than the body of the screw.

4. The combination with an incandescent electric lamp socket and a lamp bulb having a screw threaded shell entering into said socket, of a ring fitted to said socket, and a locking member movable in said ring into engagement with said lamp bulb shell; said ring being arranged in engagement with said bulb at its lower end to prevent longitudinal movement thereof on said socket.

5. The combination with an incandescent electric lamp socket and a lamp bulb having a screw threaded shell entering into said socket, of a ring fitted to said socket, and a locking member movable in said ring into engagement with said lamp bulb shell; said ring being provided at its lower end with an inwardly extending flange for engagement with the lamp bulb to prevent longitudinal movement of the ring upon said socket.

LEVI DAVIS.

In the presence of—

H. G. COOK,
E. M. HARRINGTON.
